UNITED STATES PATENT OFFICE.

SAMUEL F. DONNELL, OF SEATTLE, WASHINGTON.

CONVERTIBLE BED AND TABLE ATTACHMENT FOR AUTOMOBILES.

1,282,391.

Specification of Letters Patent. Patented Oct. 22, 1918.

Application filed May 28, 1917. Serial No. 171,385.

To all whom it may concern:

Be it known that I, SAMUEL F. DONNELL, a citizen of the United States, residing at Seattle, in the county of King and State of

5 Washington, have invented certain new and useful Improvements in Convertible Bed and Table Attachments for Automobiles, of which the following is a specification.

This invention relates to automobile accessories; and its object is the provision of devices of this character which may be interchangeably used either as a bed or a dining table and connected to the vehicle so as to be folded thereagainst when unemployed.

15 The invention consists, first, in a spring bed-frame having two foldably connected members and hingedly connected to a vehicle's running board; second, in the novel headboard and the manner of connecting it to the bed-frame to serve as either a support therefor or a table top; third, in the provision of devices which may be utilized either as table legs or as tie-pieces for rigidly securing the bed-frame members in alinement; 25 and, fourth, in the novel manner of securing the bedding in place to safeguard the same from injury.

The invention further consists in the novel construction, adaptation and combination of parts, as will be hereinafter described and claimed.

In the accompanying drawings, Figure 1 is a plan view of apparatus embodying my invention in its extended position, as when utilized as a bed. Fig. 2 is a vertical longitudinal sectional view of the same. Fig. 3 is a view in side elevation of the apparatus adapted for use as a table and illustrated by broken lines in collapsed position upon the 35 running board of a vehicle.

40 Referring to the drawings, the numeral 5 designates the so-called running board extending laterally from the body 6 of an automobile. Connected to said running board by hinges 7 is a bed-frame comprising transverse end bars 8, 9 and side rails, each of 45 the latter being formed of two elements 11, 12, respectively connected by hinges 13 ar-

ranged so that the two frame members will be in spaced relations when occupying the 50 positions in which they are illustrated in Fig. 3.

Secured to the bars 8 and 9 are the ends of a suitable spring fabric 14 to support the mattress and bedding. Connected from opposite sides to rail elements 12 by links 15 and 16 is a rectangular head-board 17, having a plane surface 18, said links being of lengths and relatively disposed to cause the head-board to be held in upright position 55 when employed as shown in Figs. 1 and 2 with the bar 9 supported on links 15; and when the frame members occupy the positions in which represented in Fig. 3 the 60 links will serve to hold the head-board between the rail elements 12 so that the surface 18 will be in a plane, or nearly so, with the 65 rail surface 12¹.

19 represent legs, one at each side of the frame, and detachably connected thereto by 70 screw-bolts 21 and winged nuts 21¹ to the rail elements 11. Said legs are desirably formed of angle bars, the lateral flange 20¹ of each being adapted to extend below the 75 respective rail element and provide a shoulder 20² upon which such element is borne when a leg is used as a support, as shown in Fig. 3.

When the frame is extended, the legs are 80 swung from the position indicated by 20¹ in Fig. 2, to the full line position and are connected to the rail elements 12 by means 85 of winged nuts 22¹ engaging the threaded ends of screw bolts 22 which extend through registering holes provided in the adjacent rail elements and legs. When thus secured 90 the legs serve to secure the frame members against folding about the hinges 13.

23 represents a strap extending transversely of the bed-frame and having its ends fastened, as at 24, to the rail elements 11. 90

A plate or board 25 is connected by hinges 26 to the frame bar 8 so as to be turned down upon the running board 5 (Figs. 1 and 2) to bridge the gap between the latter and the referred-to bar; or the plate 25 may be swung 95 against a ledge 27 secured to the bar 9 for

supporting the outer end of the associated frame member (Fig. 3) in substantially parallel relation to the other frame member when the apparatus is to be utilized as a table and also as a partition, as indicated by broken lines 25, with respect to the frame when it is turned upwardly upon the running board as represented by broken lines in Fig. 3. The function of said plate when thus used, is to prevent the mattress and bedding (not shown) from becoming soiled or wet by getting into contact with the running-board 5.

Under such conditions, the plate 25 is prevented from being withdrawn from the ledge 27 by means such as hooks 28 connected to one of the frame members engaging in staples or bolts 29 provided on the other member.

20 To releasably secure the various parts of my apparatus upon the running-board, a link 30 may advantageously be employed to connect a screw 31 detachably engaging the frame with some part of the automobile as, for example, to the lamp bracket stud 32.

The strap 23 serves to prevent the spring fabric 14 from unduly sagging when subjected to the weight of a person lying thereon, and also preventing the fabric from bulging outwardly by pressure exerted by the mattress and bedding when the apparatus is in upright position upon the running board.

To use the apparatus as a table, it can, 35 after being released from the link 30, be readily turned down from its broken line position into full line position, as illustrated in Fig. 3, to be supported by legs 19 applied to the frame. From such positions, 40 and with the legs still supporting one member of the frame, the other member is swung outwardly onto the link 15 of the head board which has meanwhile been swung into its upright position, as shown in Figs. 1 and 2.

45 Where the ground is soft or uneven, the foot-board may be seated upon an object such as a block 33.

When the frame is being extended, the legs 19 should remain in broken line position 20 (Fig. 2) so as to enable the fabric to be stretched, after the accomplishment of which the legs are swung into positions such as shown by full lines in the view, whereat they may be secured to the frame elements 55 12 to furnish a strong and rigid frame.

It may be mentioned that, in practice, I provide a bag-shaped covering of a waterproof material to fit over the apparatus when collapsed upon the running board, a 60 hole being provided in the covering to accommodate the screw 31.

What I claim, is—

1. In apparatus of the character described,

the combination with the running-board of an automobile, of a two-part frame hingedly connected to said running board, hinges connecting the parts of said frame together, means co-operating with the latter for supporting one member of said frame in substantially horizontal position, means co-operating with said hinges for retaining the frame parts in substantially horizontal relations, a fabric connected at its ends to the respective frame-parts, and means connected to said frame for selective use either 75 as a table top or as a support for the frame.

2. In apparatus of the character described, the combination with the running board of an automobile, of a frame formed of two sections connected by hinges to fold into a substantially U-shape, means to tiltably connect an end of one of said sections to said running board, means to support the other end of such section from the ground, a plate serving as a distance piece between the remote ends of said sections from said hinges, and means to detachably couple the last named ends against accidental separation and thereby retain said plate in operative position when the frame is in horizontal and 90 vertical positions.

3. In apparatus of the character described, the combination with the running-board of an automobile, of a frame formed of two hingedly connected members, hinges connecting one of said members to said running board, devices connected to the other of said members so as to serve either as a foot-board or a table-top, a spring fabric connected to the ends of said frame, a pair 100 of legs detachably connected to the free end of the frame member which is hinged to said running-board and serving with the latter to support the frame in its folded position, and means adapted to be interposed between 105 the two frame members to maintain the same in substantially parallel relations.

4. In apparatus of the character described, the combination with the running-board of an automobile, of a foldable frame comprising 110 two members, hinges connecting the adjacent ends of said members at distances apart to accommodate bedding therebetween when the frame is folded, means for tiltably connecting one of said members to said running-board, to enable the frame members to occupy upright positions on the latter, a table top, and means connecting said table-top with the frame whereby such top may be employed as a support for the frame 115 when in its extended position.

5. In apparatus of the character described, the combination with the running-board of an automobile, of a foldable frame comprising 120 two members, hinges connecting the adjacent ends of said members at distances

apart to accommodate bedding therebetween when the frame is folded, means for tiltably connecting one of said members to said running-board, bars connected to the last-mentioned frame member and coöperating with said running-board for supporting the frame, a table-top, and means connecting said table-top with the frame whereby such top may be employed as a support for the frame when in its extended position, and

means for securing said bars to one or both of the frame members to respectively serve as table-legs or reinforcement elements.

Signed at Seattle, Washington, this 21st day of May, 1917.

SAMUEL F. DONNELL.
